UNITED STATES PATENT OFFICE.

HARRY C. STICKEL, OF DAWSON, PENNSYLVANIA.

RAILWAY-CAR TRUCK.

Application filed January 10, 1925. Serial No. 1,609.

To all whom it may concern:

Be it known that I, HARRY C. STICKEL, a citizen of the United States, residing at Dawson, in the county of Fayette and State 5 of Pennsylvania, have invented new and useful Improvements in Railway-Car Trucks, of which the following is a specification:

This invention relates to improvements 10 in railway car trucks:

The object is to provide means for mounting journal boxes in the side frames of car trucks so as to securely hold the same in place without the use of bolts or nuts and 15 prevent their accidental separation under all conditions of service:

A further object is to provide a means for mounting journal boxes, which is readily formed in the manufacture of the side 20 frames and the journal boxes, the locking means consisting of simple dogs, so constructed and mounted in the side frames as to cause the automatic locking of the boxes in position, when the wheels and axles, together with the boxes mounted thereon, are 25 rolled into position beneath the frame, and the latter is lowered onto said boxes.

A final object is to provide a mounting 30 means which will permit the journal boxes to be easily removed from their positions in the frames, when the latter has been properly jacked up, by merely lifting the dogs, either by hand or by some tool to release the locking engagement, when the wheels, axle 35 and boxes may be rolled from beneath the frame.

A full and complete understanding of the 40 invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be 45 changed or modified, so long as such changes or modifications mark no material departure from the salient features of the invention, as specifically pointed out in the appended 50 claims.

In the drawing, in which similar reference characters designate corresponding parts throughout the several figures:—

Figure 1 is a side elevation of one end

of a truck frame member, showing a journal box mounted therein in accordance with the present invention;

Figure 2 is an enlarged vertical section through the same;

Figure 3 is a vertical, transverse section, 60 taken substantially on the line 3—3 of Figure 2;

Figure 4 is a horizontal section taken on the line 4—4 of Figure 2;

Figure 5 is a detail perspective view of 65 the journal box;

Figure 6 is a detail view of one of the locking dogs.

Referring to the drawing there is shown one end of the frame of a railway car truck, 70 the side frame 1 of which may be of any of the forms in common use, wherein the journal box 2 is adapted to be seated between the pedestal jaws 3 cast integrally with the said side frame.

The jaws 3 define a rectangular opening or seat in the frame, the bottom thereof being open for the purpose of sliding the box upwardly into the same when assembling the truck, and the side walls of said opening 80 or seat are provided with longitudinally extending, vertical grooves 4 extending from the upper ends to the lower ends thereof, the lower ends of said grooves being open.

Formed in the frame casting, at either 85 side of the journal box seat, the jaws 3 are provided with pockets or chambers 5, extending at an angle to said seat, the upper ends being closed, while the lower, inner ends are open and communicate with the 90 grooves at points slightly above the vertical centers thereof. The chambers are preferably oblong in cross section, and the side walls of the same are provided with elongated slots 6 extending longitudinally of 95 the chambers from a point adjacent to the bottoms of the grooves to points adjacent to the upper or outer ends of the said chambers, and the grooves of each chamber are in horizontal alignment with each other.

The journal box 2 which may be of any 100 of the well known types, is provided on each exterior side wall with spaced flanges or beads 7, which are adapted to receive the sides of the pedestal jaws 3 between the same, the said flanges or beads extending also across the top of the journal box, thus serving, not only to increase the bearing

surface of the box within its seat to hold the same rigidly therein, but to strengthen the structure of the box as well.

Midway between said flanges or beads 7, 5 the sides of the box are also provided with vertical ribs 8 formed integrally therewith, and arranged parallel with the flanges and consequently in a position to occupy the aforesaid grooves 4, when the journal box is properly seated between the pedestal jaws 3.

The ribs 8 are provided with cut-out portions or seats 9 located substantially midway of their lengths, and in position to register or aline with the lower, inner open ends of 15 the aforesaid chambers 5 when the journal box is thus seated, said cut-out portions or seats being arranged at the same angle as the adjacent chamber, as clearly shown in Figure 2 of the drawing.

20 Mounted in each chamber is a dog or locking member 10 formed of suitable metal, of a cross sectional size and shape to freely slide upwardly or downwardly within the chambers, and having its lower, or active 25 end bevelled, as at 11, to abut against the side wall of the journal box and to fit within the aforesaid cut-out portions or seats 9 between the portions of the ribs 8.

The length of the dog is such as to permit 30 the same to be raised until the upper end strikes the upper end of the respective chamber, when the lower end is entirely free of the lower end of the upper portion of the rib, when the box may be lowered and removed from the frame member.

The dogs are each provided with apertures 12 located near the terminals of the same, said apertures serving to receive the end of a suitable tool, or pointed implement, 40 when elevating the dogs out of engagement with the ribs on the journal box. Such implement may be inserted through one or the other of the aforesaid inclined slots 6, and engaged with the exposed upper aperture 12 45 in the dog, and the latter slid along its respective chamber until the lower aperture appears at the lower end of the said slot, when a similar implement may then be inserted in the same, and the dog is held up 50 and out of engagement. When the other dog is similarly released, the journal box may be removed from the truck frame member, after the latter has been jacked up in the proper manner. When assembling the 55 parts, the dogs are held up as described and, after the journal box has been placed in position and the jacks are allowed to lower the frame, the dogs will automatically lock themselves with the journal box, by 60 simply removing the holding pin, said dogs being sufficiently heavy to gravitate down the chambers and engage the seats provided for the same.

65 From the foregoing it will be seen that a simple means has been provided for locking

journal boxes in the side frame members of car trucks, the coacting parts, with the exception of the two locking dogs, being readily formed in the journal box and side frame respectively, during the process of casting the 70 same, and that such locking will be accomplished automatically without the use of bolts or nuts or similar fastening means commonly employed; and it will be further seen that the assembling and disassembling of 75 the parts may be effected without the use of special tools or other aid aside from the necessary lifting jack or jacks.

What is claimed is:—

1. Means for holding journal boxes in 80 car trucks, comprising a side frame having spaced pedestal jaws provided in their opposed faces with vertical grooves and chambers communicating with said grooves, a journal box adapted to fit between said jaws 85 and having ribs slidably engaging said grooves, said ribs being provided with seats, and dogs loosely mounted in the chambers and adapted to gravitate into said seats to hold the journal box in position.

2. A journal box for car trucks having a side frame provided with spaced pedestal jaws, the opposed, vertical faces of said jaws having longitudinal grooves extending from top to bottom thereof, said frame having interior inclined chambers between its side walls and communicating at their lower ends with said grooves at intermediate points of the latter, said journal box having vertical ribs adapted to 100 slide into the grooves when said box is mounted between the jaws, said ribs having cut-out portions to register with the lower ends of the chambers, and gravity-actuated dogs mounted in the chambers and adapted to engage the cut-out portions of the ribs to prevent the journal box falling out of the truck frame.

3. The combination with a car truck side frame having spaced pedestal jaws provided with guideways in their opposed, vertical sides, and having a chamber in each jaw arranged at an incline and communicating at their lower ends with said guideways intermediate of the lengths of the latter, the side 115 walls of said chambers having longitudinal, inclined slots, of a journal box adapted to fit between the jaws and having vertical ribs for engagement with the guideways, said ribs having inclined recesses to aline 120 with the lower ends of the chambers, and a dog mounted in each chamber and adapted to gravitate into locking engagement with the recesses.

4. The combination with a car truck side frame having pedestal jaws, said jaws being provided with vertical grooves in their opposed faces and with opposite, inclined chambers communicating at their lower ends with the grooves, said chambers having 130

their side walls provided with inclined slots extending longitudinally of the chambers, of a journal box having side ribs adapted to slide upwardly in the grooves when the 5 box is seated between the said jaws, said side ribs having inclined seats or recesses in line with the chambers, and a sliding dog mounted in each chamber to gravitate into locking engagement with the seats in the

ribs, each dog having a beveled lower end 10 to abut the side of the journal box, and having terminal openings for engagement by a pointed tool to raise the same in its chamber and release the journal box.

In testimony that I claim the foregoing as 15 my own, I have hereto affixed my signature.

HARRY C. STICKEL.
